(57) CLAIM

The ornamental design for a folding chair with sunshade, as shown and described.

DESCRIPTION

FIG. 1 is a perspective view of a folding chair with sunshade showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The bottom view of a folding chair with sunshade is being omitted since it is not visible in normal use.
